INVENTOR
Victor Hartmann
BY
Paul W. Klein
ATTORNEY

UNITED STATES PATENT OFFICE.

VICTOR HARTMANN, OF LONG ISLAND CITY, NEW YORK.

PAINTER'S DEVICE.

Application filed May 25, 1922. Serial No. 563,526.

To all whom it may concern:

Be it known that I, VICTOR HARTMANN, a citizen of the United States, and resident of 192 Lawrence St., Long Island City, in the 5 county of Queens and State of New York, have invented certain new and useful Improvements in Painters' Devices, of which the following is a specification.

This invention relates to tools in general 10 and is particularly adapted to expedite the work of painting, varnishing, cleaning, etc., of surfaces of articles, walls and the like without soiling or damaging the part of the surface not intended to be subjected 15 to the work.

One of the objects of my invention is to provide a simple, inexpensive, new article of manufacture, which may be employed in various positions.

20 Another object of my invention is to provide means whereby an appropriate handle may be attached to my device.

Another object is to provide means for attaching a receptacle in which paint, varnish, or any other liquid may be held during 25 the process of painting the object to which my device is applied.

The foregoing and further objects will be more fully apparent from the following description and the accompanying drawings, 30 showing a preferred form of my device and forming a part of this specification, and in which:

Fig. 1 is a top view of my device.

35 Fig. 2 is a side elevation thereof, shown in use.

Fig. 3 is a side elevation of my device used in a different manner.

Fig. 4 is an elevation of my device used 40 again in a different way.

Fig. 5 represents a paint receiving cup.

Referring to the drawings, numeral 10 designates the body of my device, which is preferably made of sheet metal and is provided 45 with beveled edges 11 and 12, the purpose of which will be explained later.

Made preferably integral with the body of my device are handle attaching means 13 and 14 and cup receiving or attaching means 15 and 16. These attaching means are preferably stamped out from the body of my device, so as to form loops as clearly seen in Figs. 2 and 3, into which prongs 17 of a handle 18 may be inserted. These loops 55 are so arranged as to be near both short sides of my device and in near proximity of

the one long side of my device which is not beveled.

Similarly arranged are the cup receiving means. The cup or receiver 19 is either 60 equipped with two rigid extensions 20 and 21 adapted to be inserted into receiving means 15 and 16, respectively, as shown in Fig. 2; or with one hinged extension 22 as shown in Fig. 5 to permit the cup to assume 65 always an upright position relative to the body member 10.

In use my device is rested with one of its beveled edges against the portion of an object which is to be painted, cleaned, or varnished, thus preventing the portion covered by my device from being subjected to this operation. As shown in Fig. 2, it is assumed that molding 23 is to be painted, while the 70 wall below the molding 24 is to remain unpainted.

The beveled edge 12 of my device abuts with the lowest point of molding 23 and now the painting brush passes over the molding and the beveled edge, and will apply paint, varnish, or the like to the molding without permitting it to stain the wall portion 24.

In Fig. 3 a similar molding 23' is shown upon which my device is so rested that it abuts with wall portion 24', thus permitting the painting of that wall portion while preventing paint from staining the molding 23'.

When my device is in the position shown in Fig. 2, it is necessary that cup 19 is attached to receiving means 16 into which extension 20 is inserted. In the position shown in Figs. 1 or 3, cup 19 is attached to either one of the receiving means 15 at the short ends of the body member by inserting 95 thereinto the extension 21 of the body.

The re-positioning of the cup according to application of my device may be obviated by providing a hinged extension 22 as shown in Fig. 5, whereby that extension may remain in one of the receiving means 15 or 16. The cup then may be tilted according to the position of the body member 10.

When it becomes necessary to paint corners, my device may be arranged in the way 105 shown in Fig. 4, where one of the short edges 11 may be thrust against the object to be painted. In this position the handle 18 engages the receiving means of the opposite short edge of my device, and cup 19 engages one of the receiving means 15.

In the drawings I have shown a preferred

form of my device made of sheet metal and where the receiving means 13, 14, 15, and 16 are preferably punched out from the body portion.

5 However, I shall not be limited to the specific showing and reserve for myself the right to use various other material and construct the receiving means in different ways, so as to simplify and cheapen the manufacture of the article.

10 Similarly the handle and the cup may be constructed in various different ways without departing from the broad scope of my invention, for which I claim:

15 1. A new article of manufacture, comprising a shield member provided with beveled sharp edges, a handle, a container, attaching means provided with said shield member for receiving said handle and said

container in desired relation with said shield member.

2. In a new article of manufacture, a shield member having sharp, beveled edges, and handle and container receiving means provided with said shield member.

25 3. In a new article of manufacture, the combination of a shield member having sharp beveled edges and provided with handle and container receiving means, a removable handle and a removable container, both 30 adapted to engage their respective receiving means in desired relation to said shield member.

Signed at New York in the county of New York and State of New York this 17 day of May A. D. 1922.

VICTOR HARTMANN
